(57) **CLAIM**

The ornamental design for a cord carrier for portable dialysis cabinet, as shown and described.

DESCRIPTION

FIG. 1 is a perspective view of one side and the front of a cord carrier for portable dialysis cabinet according to our design;

FIG. 2 is a perspective view of one side and the back of a cord carrier for portable dialysis cabinet in FIG. 1;

FIG. 3 is a front view of a cord carrier for portable dialysis cabinet in FIG. 1;

FIG. 4 is a back view of a cord carrier for portable dialysis cabinet in FIG. 1;

FIG. 5 is a left side view of a cord carrier for portable dialysis cabinet in FIG. 1;

FIG. 6 is a right side view of a cord carrier for portable dialysis cabinet in FIG. 1;

FIG. 7 is a top view of a cord carrier for portable dialysis cabinet in FIG. 1; and,

FIG. 8 is a bottom view of a cord carrier for portable dialysis cabinet in FIG. 1.

In the drawings, the dash-dot-dash-dot broken lines are shade lines illustrating points of tangency.
